UNITED STATES PATENT OFFICE.

WILLIAM W. HOLLOWAY, OF WHEELING, WEST VIRGINIA, AND HENRY KIELBERG, OF MARTINS FERRY, OHIO, ASSIGNEES TO WHITAKER-GLESSNER COMPANY, OF WHEELING, WEST VIRGINIA, A CORPORATION OF WEST VIRGINIA.

SUBSTRUCTURE FOR STOVES.

Application filed July 26, 1922. Serial No. 577,726.

To all whom it may concern:

Be it known that we, WILLIAM W. HOLLOWAY and HENRY KIELBERG, citizens of the United States of America, and residents, respectively, of Wheeling, county of Ohio, and State of West Virginia, and Martins Ferry, county of Belmont, and State of Ohio, have invented certain new and useful Improvements in Substructures for Stoves, of which

10 the following is a specification.

This invention relates to substructures for sheet-metal heating stoves, and it has for its primary object to provide reinforcing means for the lower, or base, portion 15 of a stove casing for affording to said portion relatively great strength and rigidity, and which also constitutes a stable mounting for the stove supporting legs.

A further object is to provide, in a sub- 20 structure for stoves, a sheet-metal leg mounting of substantial form and to which the legs may be conveniently attached.

A still further object is to provide a sub- 25 structure of the character mentioned which includes a novel and substantial form of sheet-metal leg.

In describing the invention in detail, reference is herein had to the accompanying drawings, in which:

30 Figure 1 is a vertical sectional elevation of the lower portion of a heating stove constructed in accordance with the present invention;

Figure 2 is a section on line 2—2, Fig. 1. 35 Figure 3 is a front elevation of a fragmentary portion of the stove and an attached front leg;

Figure 4 is a side elevation of the same with front and rear legs attached;

40 Figure 5 is a lower end elevation of the same;

Figure 6 is a top plan view of the upper plate of the combination reinforcing device and leg mounting;

45 Figure 7 is a section on line 7—7, Fig. 6;

Figure 8 is an edge view of the same;

Figure 9 is a bottom plan view of the lower plate or panel of said reinforcing device and leg mounting;

50 Figure 10 is a section on line 10—10, Fig. 9;

Figure 11 is a side elevation of the same;

Figure 12 is a top plan view of a rear leg; and—

Figure 13 is an inner side elevation of 55 the same.

Referring to said drawings, 1^a, 2^a and 3^a indicate outwardly pressed semi-cylindrical beads or rolls formed, respectively, upon the lower edge portion of a side wall 1, the front fender portion 2, and the rear wall 3 of a sheet-metal stove or heater casing, said rolls being located in a common horizontal plane and having their terminal edges directed inward horizontally. 65

Fitted into closely embracing relation to the opposite end portions of the roll 1^a are roll portions 4^a formed on the outer lateral edge of a narrow panel 4 which is made of sheet metal of heavy gauge so as to be relatively stiff and inflexible; and also disposed in similar relation to the adjacent end portions of the rolls 2^a and 3^a are roll portions 4^b and 4^c formed on the opposite ends of said panel 4. Said rolls 4^b and 4^c occupy 70 mitered relation to the adjacent rolls 4^a, as is shown in Fig. 9. The inner lateral edge of said panel is bent downward to form a depending stiffening flange 4^d. 75

Mounted over or above the panel 4 is a 80 substantially rectangular plate or panel 5 which has its outer lateral edge 5^a and its opposite ends 5^b and 5^c bent or curled upward to conformably fit interiorly in seated relation to the terminal edges of the rolls 85 1^a, 2^a and 3^a of the casing walls. Holes 4^e and 5^e are provided, respectively, in said panels 4 and 5, for the reception of an attaching bolt 6 whereby said panels are secured in the seated positions stated in 90 clamping relation to the rolls of the casing. Longitudinally extending ribs 4^f are preferably provided in the panel 4 for stiffening purposes, and similar ribs 5^f are preferably provided in the panel 5. One or 95 all of the ribs of one of the panels may be located in register with the ribs in the other panel, as shown at the right in Fig. 2, so that they may substantially interengage for preventing relative lateral shifting of the 100 panels when attached together by the single bolt 6.

Provided in the opposite end portions of the panels 4 and 5 are holes 4^g and 5^g de-

signed to occupy registering relation and adapted to receive bolts 7 whereby are attached a front leg 8 and a rear leg 9. The front leg is preferably of an ornamental form and may be either cast or pressed, it having a flat head portion adapted to seat against the flat under face of the front end of said panel 4. The rear leg is formed of a single sheet-metal blank pressed to form 10 a side wall 9^a and a rear wall 9^b disposed at right angles to each other and preferably having a vertical outstanding bead 9^c at the angle between said walls. The upper end 9^d of said rear leg is formed by turning the 15 end of the blank inward at right angles to the walls 9^a and 9^b and taking up the excess metal by forming therein two triangular folds 9^e. Provided in said end is a plurality of suitably located bolt holes 9^f 20 through which the attaching bolts 7 are directed.

From the foregoing, it will be apparent that each of the panels 4 and 5 complements the other in the formation of a mounting 25 for the stove supporting legs and which additionally, serves as a reinforcement whereby the lower ends of the casing walls 1, 2 and 3 are rigidly held in permanently fixed relation.

30 What is claimed is:—

1. The combination with a sheet-metal stove casing having outwardly pressed terminal rolls of approximately semi-cylindrical shape formed on the lower ends of its front, 35 side and rear walls, of upper and lower panel-members adapted to be disposed in clamping relation to the terminal edges of said rolls, the lower of said members being shaped to embrace a side-wall roll and the 40 adjacent ends of the rolls of the front and rear walls, and the upper member being adapted for having its outer lateral edge seat 45 interiorly of said side-wall roll, and means for attaching said plates together, said members being adapted for having stove supporting legs attached thereto.

2. The combination with a sheet-metal stove casing having outwardly pressed terminal rolls of approximately semi-cylindrical shape formed on the lower ends of its front, 50 side and rear walls, of upper and lower panel-like members adapted to be disposed in clamping relation to the terminal edges of said rolls, the lower of said members having its outer lateral edge shaped 55 to form a roll portion for embracing the roll of said side wall and having its oppo-

site ends shaped to form rolls for embracing the adjacent ends of the rolls of the front and rear walls, and the upper of said members being adapted to seat in overlying relation to the terminal edges of the rolls of said casing and to be rigidly attached intermediate its ends to said lower member, and means for attaching legs to said members.

60

65

3. The combination with a sheet-metal stove casing having outwardly pressed terminal rolls of approximately semi-cylindrical shape formed on the lower ends of its front, side and rear walls, of a pair of complementary members adapted to reinforce the lower end of said casing and to afford a mounting for stove-supporting legs, said members being attached together in seated clamping relation to the upper and under 70 surfaces of the terminal edges of said rolls.

75

4. The combination with a sheet-metal stove casing having outwardly pressed terminal rolls of approximately semi-cylindrical shape formed on the lower ends of its front, side and rear walls, of a pair of complementary members adapted to reinforce the lower end of said casing and to afford a mounting for stove-supporting legs, said members being detachably secured in clamping 80 relation to said rolls, the upper member being fitted to seat interiorly with respect to said rolls, and the lower member being fitted to embrace said rolls exteriorly.

85

5. The combination with a sheet-metal stove casing having outwardly pressed terminal rolls of approximately semi-cylindrical shape formed on the lower ends of its front, side and rear walls, of a pair of complementary members adapted to reinforce the lower end of said casing and to afford a mounting for stove-supporting legs, said members being detachably secured in clamping 95 relation to said rolls, the upper member having its opposite ends seated within the rolls of the front and rear walls and its outer lateral edge seated within the roll of the adjacent side wall, and the lower member having its outer lateral edge and its opposite ends, respectively, disposed in embracing 100 relation to portions of the side-wall roll and the front and rear wall rolls.

105

In testimony whereof we affix our signatures in presence of two witnesses.

WILLIAM W. HOLLOWAY,
HENRY KIELBERG.
